UNITED STATES PATENT OFFICE.

RALPH L. NELSON, OF GRAND RAPIDS, MICHIGAN, ASSIGNOR TO CHARLES G. WILLETT, OF GRAND RAPIDS, MICHIGAN.

ROAD SCRAPER.

Application filed April 18, 1927. Serial No. 184,655.

This invention relates to road scrapers and is more particularly concerned with an adjustable scraper adapted to be attached to the chassis of a motor truck and having 5 means of adjustment whereby the angle of the scraper with respect to the chassis may be changed and adjusted so that the scraper may occupy a number of different angular positions and enable it to scrape either side 10 of the road irrespective of the direction in which it is going. It is also possible to adjust the scraper so that it lies at right angles to the length of the truck and in such position adjust the scraper longitudinally a limited distance in either direction.

It is a primary object and purpose of the present invention to provide a simple, practical and effective means for thus adjusting the scraper blade thereby making the scraper 20 much more effective than heretofore. A further object of the invention is to provide such adjustment and at the same time retain a practical and effective means for raising and lowering the scraper with respect to the 25 road surface, such means being the subject matter of a prior patent to David E. Burns, No. 1,625,019, granted April 19, 1927.

An understanding of the invention may be had from the following description taken 30 in connection with the accompanying drawings, in which,

Fig. 1 is a side elevation of a truck equipped with my invention.

Fig. 2 is a fragmentary plan view showing the truck frame and the scraper adjustably mounted thereon, there being also indicated various angular positions which the scraper may occupy.

Fig. 3 is a fragmentary plan view with 40 some parts broken away illustrating the manner in which the scraper supporting bar is mounted upon the truck frame, and

Fig. 4 is a side elevation of the construction shown in Fig. 3, with some parts shown 45 in vertical section and the scraper illustrated in two different positions, one in full and the other in dotted lines.

Like reference characters refer to like parts in the different figures of the drawings.

The motor truck on which the scraper is to be mounted may be of any conventional construction, the chassis side frame members being indicated at 1. To each of the side 55 members 1, a metal supporting and guide

bar is permanently secured, each comprising a flat horizontal section 2 located a short distance below and parallel to the lower side of the frame member 1 with which it is associated, and at each end being twisted at 60 right angles and turned upwardly at right angles to make the attaching arms 3 which are bolted securely to the frame member 1 above it.

A beam or bar 4 preferably of channel iron is located below the horizontal bars 2 and adjustably mounted thereon by means of heavy metal clips which each have an intermediate portion 5 and ends 6 bent to lie in a plane below the plane of the intermediate portion. These clips pass over the horizontal parts 2 of the guide and supporting members so that the bar 4 is mounted for movement on the guide bars 2. The lengths of the intermediate portions 5 of the clips 75 are greater than the width of the guide bars 2.

A plurality of brackets 7 are secured in spaced apart relation to the under side of the bar 4 and carry a shaft 8 rotatably mounted thereon, on which the scraper blade 9 is mounted by means of springs 10 in a manner like that shown in Patent No. 1,429,125, issued to David E. Burns, on the 12th day of September, 1922.

An arm 11 is rigidly secured to the shaft 8 substantially midway between its ends and is connected by a link 12 to the rear end of a lever 13, pivotally mounted between its ends on a bracket 14 which extends downward from the chassis of the motor vehicle. A vertical shaft 15 equipped with a hand wheel at its upper end is mounted for rotation adjacent the driver's seat of the vehicle at one side of the chassis and has a screw 95 and nut connection, indicated at 16, with the front end of the lever 13. This is for the purpose of rocking the shaft 8 to different positions for raising and lowering the scraper blade 9 with respect to the surface of the 100 road over which it is passing. It is substantially like that shown in the patent first referred to.

Set screws 17 thread through the sections 5 of the clips so as to bear at their lower 105 ends against the guiding and supporting bars 2 and thereby hold the clips rigidly in position with respect to said bars. In addition hook members 18 (see Fig. 4) adapted to engage with the flanges of the 110

channel bar 4 are located below each of said bars 2 and screws 19 and 19^a pass downwardly through the bars 2 and thread into said hook members so that the same may be clamped tightly against the edges of the flanges of bar 4 and aid in holding said bar in the positions to which it may be adjusted. A plurality of holes are made through the bar 2 spaced at equal distances apart so as to define predetermined positions that the screws 19 are to take and in this manner define various positions of the scraper supporting bar 4. A brace bar 20 is pivotally connected to the outer side of each of the frame members 1 by means of a bolt 21 and at its lower end is formed with a foot 22 adapted to come against the upper side of the guiding and supporting bar 2 below it. The foot 22 has an opening therein so that one of the screws 19^a may pass through the foot when it at the same time passes through the bar 4 to engage with the hook member 18 as shown in Fig. 4.

It is evident from the foregoing description that the bar 4 which carries the scraper may be adjusted to many different positions. It is shown in one position in Fig. 2. By loosening the set screws 17 and by removing the set screws 19 and 19^a, this bar may be swung to any of the positions indicated by dot and dash line in Fig. 2. It also may occupy two other positions, but such positions, as they would be merely parallel to two of the positions already indicated, are not shown in Fig. 2. The scraper may be reversed so as to scrape to either side of the road irrespective of the direction in which the truck is going.

It is also evident that in the position directly across the truck, or at right angles thereto, the scraper may shift longitudinally a limited distance, in practice about 6 inches, due to the length provided by the raised sections 5 of the attaching clips greater than the width of the bars 2.

When the bar 4 is shifted from the position in Fig. 4 to the other indicated in dotted lines in the same figure the diagonal brace 20 is turned around so that it will occupy the dotted line position shown. The holes through which the screws 19 and 19^a pass are equally spaced so that said screws 19 and 19^a may connect with the hook members 18 when the channel bar 4 is at the middle or intermediate position.

This construction is very practical and effective, relatively simple to produce, is strong, durable and efficient. The reversibility of the scraper as to the direction in which material will be scraped is very desirable. In those cases where the scraper is at right angles to the length of the body, it being used in such position for smoothing off relatively small protrusions and hummocks in the road, it is many times very

desirable to shift the scraper bar longitudinally and the construction which I have devised readily permits this. The invention is defined in the appended claims and is to be considered comprehensive of all forms of structure coming within their scope.

I claim:

1. In combination, a truck frame having chassis side frame members, bars attached one to each side frame member and located below and having flat horizontal portions parallel thereto, a scraper carrying beam located across and below said horizontal portions of the bars, a scraper carried by and depending below said beam, and clips attached to the upper side of said beam having elevated middle portions passing over the horizontal portions of said bars whereby the beam with the attached scraper may be adjusted to different angular positions with respect to the longitudinal center line of the truck frame and may also have a limited longitudinal adjustment.

2. In combination with a truck frame having spaced apart chassis side frame members, horizontal supporting and guide bars attached one to each frame member and located parallel to and a short distance below said frame members, a scraper carrying beam extending across and below said supporting and guide bars, a scraper carried by and depending from said beam, metal clips attached to the upper side of said beam having elevated intermediate portions longer than the width of the supporting and guide bars, and means for securely yet detachably connecting the beam with the guide bar on which it is mounted.

3. In combination with a truck having spaced apart chassis side frame members, supporting and guide bars attached one to each frame member having a horizontal portion located below and parallel to the side frame member on which it is mounted, a scraper carrying beam extending below and against said horizontal portions, means for mounting the beam on said bars whereby it may be adjusted to different angular positions and also may have a limited longitudinal adjustment and means for securely yet detachably holding said beam on the supporting and guide bars in the position to which it is moved.

4. In combination with a motor truck having spaced apart chassis side frame members, supporting and guide bars attached one to each side frame member of the truck and having horizontal portions lying below and parallel to said side members of the truck, a scraper carrying beam extending across and underneath said horizontal portions, heavy metal clips attached to said beam formed with elevated intermediate portions longer than the width of said horizontal portions passing over said horizontal portions, and

set screws extending downwardly through said elevated portions of the clips and engaging against the upper sides of the horizontal portions of the supporting and guide bars.

5. In combination a truck frame having spaced apart chassis side frame members, bars located one below each side frame member parallel thereto and provided at their ends with upwardly extending attaching sections permanently secured to the frame members of the truck, said bars having a plurality of spaced apart openings therethrough, a scraper carrying beam located below and extending across said bars, means for slidably mounting the beam on the bars whereby it may be shifted to different angular positions with respect thereto, and means extending through the openings in said bars 10 and detachably connected with said beam for holding the beam in a position to which it is adjusted.
15. In combination with a motor truck having spaced apart chassis side frame members, flat bars lying in the same horizontal plane located one below each side frame 20
- 25

member parallel thereto and permanently connected therewith, a scraper carrying beam of channel form having downwardly extending flanges located below and extending across said bars, said bars having a plurality of spaced apart openings therethrough, means for slidably supporting and guiding said beam on the bars, screws passing downwardly through selected openings in the bars at each side of said beam, and hook members engaged with the lower edges of the flanges of said beam into which said screws thread, substantially as and for the purposes described. 30

7. A construction containing the elements in combination defined in claim 6, combined with braces pivotally connected adjacent their upper ends one with each side frame member of the truck, and at their lower ends having each a foot lying against the upper side of the beam carrying bar, certain of said screws passing through the bars and engaging with the hook member also passing through said feet. 35

In testimony whereof I affix my signature.
RALPH L. NELSON. 40
